GUARD FENCE

Alfred K. Pehrson, Bellevue, Pa., assignor to
Pressed Steel Car Company, Pittsburgh, Pa., a
corporation of New Jersey

Application February 9, 1932. Serial No. 591,784

14 Claims. (Cl. 256—13.1)

My invention pertains primarily to such fences as are placed upon bridges to afford protection for pedestrians and also to prevent vehicles from running over the edges of such bridges. It is contemplated that my invention can be used upon other guard fences where the same or similar problems are encountered as in placing such fences on bridges.

Guard fences of this nature must provide for variations in the length of the bridge or other supporting structure caused by changes in temperature. At one or more places on the bridge, expansion joints are provided depending upon the design of the bridge. The total movement between the adjacent ends of the bridge at the expansion joint is considerable and the guard fence must provide for this.

In these days of high speed vehicular movement over highways and bridges these guard fences must be made strong enough to prevent the vehicles from passing through the fences should they get out of control and strike the fence and in order to effect such protection the adjacent ends of the fence rails on opposite sides of the fence post are secured together independently of the post by means of a tie passing through the post and anchored in the adjacent rail ends.

An object of my invention is to provide a guard fence of the above type with an expansion joint to accommodate the bridge movement.

Another object of my invention is to provide an expansion joint which will distribute the movement between the posts and rails at the joint so as to maintain a slight appearance in the fence at the joint.

As illustrated in the drawings, Fig. 1 shows in elevation a portion of a guard fence and an expansion joint of a bridge upon which bridge the fence is mounted; Fig. 2 shows in enlarged detail the tie between the rail ends adjacent the expansion joint; Fig. 3 is a section taken along the lines 3—3 of Fig. 2; Fig. 4 shows a modification of my invention in which a two piece post is used; Fig. 5 is an enlarged view of the tie between the adjacent rail ends and two piece post; Fig. 6 is a section of the expansion post taken along the lines 6—6 of Fig. 4; Fig. 7 is a modification of the post of Fig. 4 showing a portion of the post and base therethrough; Fig. 8 is a section taken along the lines 8—8 of Fig. 7.

The guard fence of Fig. 1 comprises spaced fence posts 1 having rails 2, 3 and 4 filling the spaces therebetween and preferably supported on lugs 5, 6 and 7 disposed on opposite sides of the posts 1. The spaces between the rails are prefer-

ably filled by panels 8 which are of any desired shape and are secured thereto in any suitable manner. The ends of the rails disposed on opposite sides of the post are tied together by a bolt 9 or other suitable tie and the ends of the bolt 9 are anchored in the rail ends. The fence thus far described is similar to that shown and described in a pending application of Luther L. Knox, Serial No. 558,225, filed August 20, 1931.

The bridge floor 10 to which the fence is secured has an expansion joint 11 therein which provides for variations in the length of the bridge due to temperature changes. The fence is so disposed upon the bridge floor 10 that a post 1^a is mounted on each side of the expansion joint 11 and the rails 2^a, 3^a and 4^a between such posts are spaced from the post to provide for variations in the post spacing as the parts 10^a and 10^b of the bridge move towards or away from each other.

It will be readily apparent to those skilled in the art that any number of expansion joints may be used in constructing the bridge depending upon the design of the supports therefor. In the event that the expansion joints are placed at the ends of the bridge the part 10^a could be 80 the end of the roadway adjacent the ends of the bridge and 10^b the ends of the bridge. Thus the herein described invention is adaptable to meet any type of bridge or equivalent structure on which the fence is mounted and where expansion must be taken care of at certain spaced points instead of being distributed throughout the length of the fence.

In assembling the fence the posts 1 are anchored upon the supporting structure and the rails 2, 3 and 4 with their attached panels 8 are mounted between the posts upon the lugs 5, 6 and 7. The tie rods 9 are inserted through the members 12 secured adjacent the ends of the rail and extending transversely thereof and then through the posts 1. Spring washers are placed upon the ends of the tie rods 9 and nuts are placed on the ends of the rods adjacent the lock washers securing the tie in place in the post and anchoring it between the members 12. It will be noted from the drawing that the ends of the rails 2, 3 and 4 stop short of the posts 1 and the members 12 within the rail ends are spaced from the lugs 5, 6 and 7. This spacing

permits expansion of the individual rails between the posts which is very slight and the lock washers keep the joint tight thus preventing rattling as the bridge vibrates under traffic.

At the two posts adjacent the expansion joint 11 where the spacing of the post 1^a will vary con-

siderably provision must be made for the changes both in the relation between the posts and rails and between the tie rods, the posts and rails. As regards the rails let us assume the expansion joint 11 is designed to provide a 2" expansion and a 2" contraction from the normal position as shown in Fig. 1. This means the posts 1^a will move towards each other a maximum of 2" from the normal position during the maximum expected rise in temperature and will be separated an additional maximum of 2" from normal during the extremely low temperatures. Obviously the posts 1^a and adjacent posts 1 on the portion 10^a and 10^b of the supporting structure will move as a unit with this portion so that there will be relatively little movement between these posts and the adjacent rail ends. In the above premise the ends of the rails 2^a, 3^a and 4^a are spaced from the posts 1^a a minimum of 1" and the ends of the lugs 5^a, 6^a and 7^a extend within the ends of such rails a distance greater than 1" so that when the posts are separated their maximum distance the rails will still be supported upon the lugs and when the posts move towards each other, the minimum distance between the posts will be slightly greater than the length of the rails to prevent distortion of the rails and posts. The members 12 secured within the rails adjacent the ends thereof and extending transversely of the rails are preferably spaced so that the lugs on the posts will not engage with them at any time. The tie rods 9^a are of sufficient length to accommodate movement of the posts and to permit the springs 13 or other resilient means to be mounted thereon between the nuts at the ends of the rods and the members 12 of the rails. These springs 13 are of such length that when the posts 1^a have separated their maximum possible distance, the springs have not compressed their maximum amount and when the posts 1^a are moved towards each other so that the minimum spacing is obtained there remains some tension in the springs. The springs are preferably made relatively stiff so that during the time the bridge is in normal position considerable pressure is exerted upon the tie rods and members 12. This pressure will tend to prevent binding at any one of the posts and maintain the rails spaced equally from the posts and improve the appearance of the fence. The resulting action of the springs, which it will be observed are opposed to each other, maintains the rails and attached panels under pressure so that that portion of the fence literally floats upon their supporting lugs secured on the adjacent sides of the posts 1^a.

From the foregoing description it will be apparent that a guard fence has been provided which comprises rails secured together independently of the supporting posts and which provides for expansion at the joints between the fence at opposite sides of the expansion joints in the supporting structure. Further, by use of the springs the appearance of the fence at the joint is preserved by maintaining the rails equally spaced between the supporting posts as well as maintaining tight connections at each end of the rail and adjacent posts to prevent rattling when the bridge vibrates from traffic.

Referring now to Figs. 4 to 8 inclusive of the drawings, it will be noted that the fence and supporting structure are in all respects similar to that shown in the preceding figures of the drawings excepting that all of the movement of the bridge at the expansion joint is taken up by an

expansion post 15 which is functionally two posts, one mounted on each of the adjacent ends of the bridge at the expansion joint and each having one end of the fence mounted thereon. Tie rods 14 similar to those of the previously described fence are passed through both of the portions 15^a and 15^b of the expansion post 15 and the ends of the rod 14 are secured within the rails 2, 3 and 4 on the opposite sides of the post 15. A spring 19 is mounted upon one end of the tie rod 14 adjacent the members 12 of the rails so that as the portions 15^a and 15^b of the post separate during movement of the portions 10^a and 10^b of the bridge the effective length of the tie rods 14 is increased to accommodate such movement. Referring to Fig. 4 of the drawings it will be noted that the ends of the rails are against the outer faces of the expansion post while a small amount of clearance is allowed between the other ends of the rails and the posts 1 secured to the portion 10^a of the bridge. As previously stated the expansion post 15 is functionally two posts, the portion 15^b and attached fence moving as a unit with the portion 10^a of the bridge and the portion 15^a and attached fence moving as a unit with the portion 10^b of the bridge. In order to maintain the appearance of the post at the expansion joint the portion 15^a may be provided with a portion 15^c which extends between the portions of the post 15^a and 15^b and a sufficient distance with the portion 15^b so as to give the appearance at all times of a single post as the portions 15^a and 15^b move towards or away from each other. This portion 15^c can be made as an integral part of the portion 15^a of the post or can be made as a separate part and secured to the portion 15^a. These forms are better shown by reference to Figs. 6 and 8 of the drawings which are taken along the lines 6-6 and 8-8 of Figs. 4 and 7 respectively. In Fig. 8 the portion 15^a of the post has a removable plate 15^d which provides access to the interior of the post if, for any reason, such should be necessary.

As stated before since the fence and posts secured to the portion 10^a of the bridge moves as a unit and the fence and posts secured to the portion 10^b of the bridge moves as a unit it is only necessary that the spring 16 have sufficient movement to accommodate the maximum movement between the portions 15^a and 15^b of the posts. The springs providing for the variations in the effective length of the tie rods 14 and serving at the same time to maintain a tight joint between the portions 15^a and 15^b of the post and their attached rail ends.

Having thus described the invention what I claim as new and desire to secure by Letters Patent is:

1. In a guard fence comprising a plurality of spaced posts, connecting rails supported on said posts, an independent tie connecting adjacent ends of said rails, an expansion joint between two of said posts and means on the adjacent rail ties permitting movement between said latter posts and the rail between them.

2. In a guard fence having two adjacent posts variably spaced apart to provide for longitudinal changes in length of the fence due to temperature changes, guard rails between the two said posts and of less length than the minimum spacing of the posts, a connection between the ends of said rail and said posts, and means associated with each connection resiliently urging said rail toward said post.

3. In a guard fence, spaced posts, guard rails supported by said posts and extending therebetween, a connecting member extending through each of said posts and extending beyond each side thereof, said member having the ends thereof removably secured within the ends of the adjacent rails, the rails between two of said posts being of a length substantially less than the space between said posts and the ends of the member extending within said rails having resilient means between the ends of the member and the means securing same within the rail. 80
4. In a guard fence spaced posts, rails extending between said posts and supported thereby, a tie extending through said posts and anchored in the adjacent ends of said rails, one of said posts being divided longitudinally for movement longitudinally of said fence, and resilient means at one end of said ties to permit movement of said posts. 85
5. In a guard fence in combination a post, rails on opposite sides of said posts, a tie passing through said posts and having its ends secured in said rails, means on said post providing expansive movement transversely thereof and means on said tie providing for the movement in said post. 90
6. In a guard fence a series of posts, rails extending between said posts, a tie securing together adjacent ends of said rails independently of said posts, one of said posts being in two portions movable in a horizontal direction with relation to each other, a coil spring encircling one end of said tie adjacent said post. 95
7. In a guard fence in combination, a post having an expansion joint extending longitudinally thereof, guard rails having adjacent ends supported by said post, transverse members secured within said rails adjacent said post, a tie member passing through said post and transverse members, stops on the ends of said members and resilient means on said tie member between one end thereof and the adjacent transverse member of the rail. 100
8. In a guard fence in combination, a pair of fence posts mounted adjacent each other, railings secured to the oppositely disposed sides of said posts, a connecting member secured within said railing and extending transversely of said posts. 105
- 50
- 55
- 60
- 65
- 70
- 75
- posts and resilient means mounted on one end of said tie to permit separation of said posts in a direction longitudinally of said railing.
9. In a guard fence comprising spaced posts secured to a supporting structure, an expansion joint for said structure between two of said posts, guard rails between and supported by said latter posts and resilient means operatively associated with said rails and posts for controlling the relative movement of said posts to the rails. 110
10. In a guard fence comprising spaced posts, guard rails extending between and supported by said posts, an expansion joint in said fence permitting relative movement of two of said posts and its connecting rails, and resilient means operatively associated with said rails and posts for centering said rails between said posts during all spacing of the posts. 115
11. In a guard fence, in combination, spaced posts, rails connecting said posts and supported thereon, a member connected to adjacent ends of said rails on opposite sides of the posts and resilient means operatively associated with said member providing for variations in the length of said fence during temperature changes. 120
12. In a guard fence, in combination, spaced posts, guard rails between and supported on said posts, a member extending through said posts with its ends anchored in the rails on opposite sides of the posts and resilient means operatively associated with one of the members so as to permit variations in the length of said fence under temperature changes. 125
13. In a guard fence comprising spaced posts, guard rails extending between and supported on said posts, an independent tie connecting the rails on opposite sides of said posts, an expansion joint providing variable spacing between two of said posts and resilient means between the rail and ties connecting said latter two posts. 130
14. In a guard fence comprising a plurality of spaced posts, rails supported on and connected to said posts, the posts supporting one of said rails being movable transversely of said rail and resilient means on said rail connecting means maintaining the rail equally spaced between the posts. 135
